Primary Examiner — Susan Bennett Hattan*Assistant Examiner* — Lauren D McVey(74) *Attorney, Agent, or Firm* — Nixon & Vanderhye P.C.(57) **CLAIM**

The ornamental design for a paper sheet sorting and counting machine, as shown and described.

DESCRIPTION

FIG. 1 is a first front right perspective view of a paper sheet sorting and counting machine showing my new design; FIG. 2 is a second front right perspective view thereof; FIG. 3 is a front elevation view thereof; FIG. 4 is a rear elevation view thereof; FIG. 5 is a right side elevation view thereof; FIG. 6 is a left side elevation view thereof; and, FIG. 7 is a top plan view thereof.

The broken lines immediately adjacent to the shaded areas in FIGS. 1, 2, and 4 depict the bounds of the claimed design, while all other broken lines are directed to environment. In addition, the unshaded surfaces that directly adjoin the claimed solid line edges form no part of the claimed design.
